Bert J. Klein and Andre Bus, Altavista, and John B. Thorn, Lynchburg, Va., assignors to The Lane Company, Inc., Altavista, Va., a corporation of Virginia

Original design application Apr. 19, 1965, Ser. No. 84,863, now Patent No. 205,620, dated Aug. 30, 1966. Divided and this application May 23, 1966, Ser. No. 2,847

Term of patent 14 years

(Cl. D33—6)

The figure is a perspective view of an armoire, embodying our new design.

The side not shown is like the side shown while the back is plain and unornamented.

This application is a division of my copending application, Serial No. D. 84,863, filed April 19, 1965, and now Patent No. D. 205,620.

We claim:

The ornamental design for an armoire, as shown and described.
